Inventor,
Hans Skreberg

UNITED STATES PATENT OFFICE.

HANS SKREBERG, OF BIG BEND TOWNSHIP, CHIPPEWA COUNTY, MINNESOTA.

HOLDER FOR SHARPENING HONES.

Application filed April 14, 1919. Serial No. 290,053.

To all whom it may concern:

Be it known that I, HANS SKREBERG, a citizen of the United States, and a resident of Big Bend Township, in the county of Chippewa and State of Minnesota (whose post-office address is Milan, Minnesota), have invented certain new and useful Improvements in Holders for Sharpening Hones, of which the following is a specification, reference being had to the accompanying drawings.

In devising my present invention I have had in mind the need of a cheap, efficient and durable means for sharpening all kinds, of tools and instruments requiring a keen edge, among which may be mentioned household and office as well as pocket knives, scissors, etc., shop tools and instruments.

My sharpening hone can be carried readily in a pocket or tool kit, and may be fastened to a bench, table or to the wall if desired. It is light in weight and for the abrasion surface provided is very small and compact.

The operation of this invention being so familiar to all, inasmuch as it is practically what is termed a "whetstone," I will merely give a clear and concise description of the same and now refer to the drawings in which:

30 Figure 1 is a perspective of my improved sharpening hone and holder.

Figure 2 is an end view thereof.

Figure 3 is a perspective view of the partly formed holder.

35 Similar reference numerals designate corresponding parts throughout the several figures of the drawings.

As will be seen in Figure 1 of the drawings the base of my sharpening hone is formed of a single piece of sheet metal of the shape substantially as shown. A represents the bottom, B, B the sides, bent along dotted lines B' at right angles to base A, and C—C represents the two flanges which engage the sharpening block D. The said flanges are bent at right angles to the body members B of the base A as indicated by dotted lines C'. The four offset retaining tongues designated E—E—E—E, are bent at right angles to

the side walls B and prevent longitudinal 50 displacement of the sharpening block D. The two semi-circular ears F—F having holes therein are bent at right angles to base A, or left in the plane thereof as shown, all depending on the use made of the article; 55 whether it is carried in the pocket or secured to a bench, table or wall.

The sharpening block D is preferably made from wood, and is cut across the grain and so that the edge grain (two sides each being reversible) forms the cutting face and is provided with the longitudinal recesses or grooves G, G along its sides as shown in Figure 2. This wood block is thus held from warping or displacement in the base 65 A, by means of the jaws C, C, which engages the grooves G, G in the wood block D.

As shown in Figure 1 the retaining members E, are bent so as to secure the end of block D in the base A.

The drawings plainly show every part of the device as well as method of constructing the whole. The wood block D is preferably saturated with an oil, and before being used the first time a small quantity of powdered 75 emery or like abrasive is spread on the cutting face of block D, if the application of such cutting compound is not done at time of manufacture.

I claim:—

80 A holder for sharpening hone blocks having holding grooves in opposite sides thereof, said holder including a body having perforated attaching ears at each end thereof lying in the same plane as the body, upright 85 walls formed from the sides of the body and having inwardly offset holding flanges for engaging in the grooves of the hone block, and locking tongues on the vertical edges of the upright walls adapted to engage with 90 the opposite ends of the hone block to prevent withdrawal thereof in the direction of the grooves therein.

HANS SKREBERG.

In presence of:

V. H. ANDERSON,
J. A. ANDERSON.
